PUSH POLE STRUCTURE

Ellsworth W. Austin, Cedar Rapids, Iowa, assignor to La Plant-Choate Manufacturing Co., Inc., Cedar Rapids, Iowa, a corporation of Delaware

Application January 27, 1941, Serial No. 376,040

12 Claims. (Cl. 37—144)

My present invention relates to a push pole structure which is used in connection with road-builders or bulldozers.

One object of the invention is to provide a "floating" type of push pole which includes a pair of members that may either float relative to each other or be locked in any one of a number of adjusted positions with relation to each other.

Another object is to provide a push pole which may be fabricated of steel plates welded together and which includes relatively rugged pivot members and a latch mechanism which may be selectively locked in either a latched position or an unlatched position, the latter position permitting the floating operation of the push pole.

A further object is to provide a push pole which may be adjusted for floating operation so as to allow the ends of a roadbuilder blade or the like to follow irregular ground contour and thereby effect such operations as clearing the overburden for a layer of coal or the like.

With these and other objects in view my invention consists in the construction, arrangement and combination of the various parts of my device, whereby the objects contemplated are attained, as hereinafter more fully set forth, pointed out in my claims and illustrated in the accompanying drawing. Although the invention is susceptible of a variety of embodiments, it is unnecessary to fully describe and illustrate more than one in order to give a full understanding of the invention both from its structural and functional standpoints. Accordingly, I have illustrated a preferred and desirable embodiment of the invention in the accompanying drawing, in which:

Figure 1 is a perspective view of a roadbuilder mounted on a tractor and including a pair of push poles of my present invention.

Figure 2 is a sectional view on the line 2—2 of Figure 1 to show the connection of the front end of the push pole with the road-builder blade.

Figure 3 is an enlarged side elevation of the push pole structure per se showing three different positions to which it may be adjusted.

Figure 4 is a plan view of the push pole structure; and

Figures 5 and 6 are enlarged sectional views on the lines 5—5 and 6—6 respectively of Figure 3.

On the accompanying drawing I have used the reference character T to indicate generally a tractor of the track-laying type. Push arms 10 are pivoted to track frame brackets 12 mounted

on the track frames 13 of the tractor. The arms 10 have a cross piece 14 at their forward ends to the center of which a roadbuilder blade 15 is pivotally secured. The roadbuilder blade may be controlled as to elevation by hydraulic jacks 16 operating bell cranks 17 and links 18. The foregoing parts are now provided in most types of roadbuilders.

My present invention centers around a push pole structure indicated generally at PP. Two of the push poles are pivoted one for each push arm 10, but I will describe only one of them as they are identical.

The push pole PP includes first, second and third members. The first member consists of a plate 19 having an upper flange 20 and a similar lower flange 21. The flanges 20 and 21 are provided with reinforcing members 22 and 23 respectively which form perforated ears at the rear end of the push pole. Intermediate the ends of the push pole, upper and lower perforated ears 24 and 25 are also provided, short straps 26 being used as reinforcements and connecting members therefor. The parts 24, 25 and 26 are secured to the parts 20 and 21 preferably by welding.

The perforations of the ears 22, 23, 24 and 25 are adapted to selectively receive a vertical pin 27 (see Figure 1) for mounting the push pole on the push arm 10. Figure 1 shows the arrangement such that the right-hand end of the blade 15 is in advance of its left-hand end. The pin 27 may be removed and replaced in a perforation 28 when adjusting the blade 15 to a position at right angles to the line of travel or may remain in the perforation 28 and coat with the ears 24 and 25 when reversing the angle of attack of the blade 15.

The second member mentioned includes a plate 29 pivoted at its rear end on a pin 30, the pin 30 is carried by the plate 19 and by a reinforcing plate 31. The plate 31 is spaced from the plate 19 so as to receive the plate 29 between them and has upper and lower inturned flanges 32 welded to the reinforcing ears 22.

The forward end of the plate 29 is perforated to receive a pivot pin 33. The pin 33 is carried by the third member which consists of a plate 34 having a plurality of vertically spaced ears 35. A reinforcing plate 36 similar to the plate 31 is also provided for the third member with the front end of the plate 29 received between the elements 34 and 36. The front and rear ends of the plate 29 are also provided with bushings 37 surrounding the pivot pins 30 and 33 and welded

to the plate 29 to provide a longer and better wearing bearing on the pivot pins.

The ears 35 of the third member are secured to the back of the blade 15 as by a vertical pin or key 38 extending through perforations 39 of the ears 35 and through similar perforations of a bracket 46 (see Figure 2).

The front end of the plate 19 is provided with three notches indicated at 41, 42 and 43. The plate 29 is provided with a slot 44 adapted to register with any one of the notches 41, 42 or 43. A pair of spaced flanges 45 and 46 are welded to the outer surface of the plate 29 to reinforce it and to provide means to support a pivot pin 47. Pivoted on the pin 47 is a latch plate 48.

The latch plate 48 is adapted to project through the slot 44 and into a selected one of the notches 41, 42 or 43 as shown by solid and dotted lines in Figure 4 and by dotted lines in Figure 5. The latch plate 48 may be latched in such position by a bolt 49 extending through perforations 50 in the flanges 45 and 46. When it is desirable to have the push pole operate floatingly however, the latch plate 48 may be swung to the position of Figure 3 (dash line position in Figure 4 and full line position in Figure 5) and locked in such position by the bolt 49 through perforations 51 in the flanges 45 and 46.

A plate 52 is secured to the plate 29 adjacent the forward end of the plate 19 and is of offset character so as to provide a space in which the plate 19 may vertically slide yet confine the plates 19 and 29 to a position closely adjacent each other. The plate 52 is provided with a slot to receive the latch plate 48.

My construction obviously provides a means for adjusting the push pole so that it is rigid in any one of three adjusted positions so that the blade 15 may have either end lower than the other to a predetermined degree. It is also adjustable so that the ends of the blade may float up and down to follow the contour of the ground when such operation is desired. The adjustment is readily accomplished and locked as desired by the bolt 49 after which operations of the roadbuilder may be resumed.

When the blade is adjusted to an inclined position, or when it moves to an inclined position when set for floating operation, such inclination is permitted by a degree of looseness in the joints between the pins 38 and the slot-like openings 39 of the ears 35.

The construction of the push pole is such that it may be used for a variety of operations heretofore unsatisfactorily performed with a push pole of rigid, non-adjustable and non-floating character. My push pole has the advantage however of being locked in a rigid position when desired.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In a push pole structure, a first member adapted to be secured to a push arm of a roadbuilder or the like, said member having a plurality of vertically spaced recesses adjacent its forward end, a pivot pin carried by said member adjacent the rear end thereof, a second member pivoted on said pivot pin and extending forwardly alongside said first member, means ad-

jacent the front end of said first member to retain said members in adjacent positions with respect to each other, a latch pivotally carried by said second member and adapted to selectively coact with any one of said recesses of said first member, means for locking said latch in any selected coacting position to rigidly fix said second member relative to said first member or in non-coacting position to permit floating of said second member relative to said first member, and means at the front end of said second member to pivotally secure it to a roadbuilder blade.

2. A push pole of the character described comprising a first member adapted to be secured to a push arm of a roadbuilder or the like, a pivot pin carried by said member, a second member pivoted on said pivot pin and extending forwardly alongside said first member, means to retain said members in adjacent relative positions with respect to each other, a latch carried by one of said members and adapted to selectively coact with the other member, means for locking said latch in such coacting position to rigidly fix said second member relative to said first member or in non-coacting position to permit floating of said second member relative to said first member, and means to secure said second member to a roadbuilder blade.

3. In a push pole structure, a first member adapted to be secured to a tractor operating a roadbuilder or the like, said member having a notch adjacent its forward end, a pivot pin carried by said member adjacent the rear end thereof, a second member pivoted on said pivot pin and extending forwardly alongside said first member, a latch adapted to selectively coact with said notch of said first member, or to assume a non-coacting position to permit floating of said second member relative to said first member, and means at the front end of said second member to pivotally secure it to a roadbuilder blade.

4. A push pole structure comprising a first member adapted to be secured to a tractor operating a roadbuilder or the like, said member having a plurality of vertically spaced notches in its forward end, a pivot pin carried by said member adjacent the rear end thereof, a second member pivoted on said pivot pin and extending forwardly alongside said first member, a latch pivotally carried by said second member and adapted to selectively coact with any one of said notches of said first member, means for locking said latch in any selected coacting position to rigidly fix said second member relative to said first member, and means at the front end of said second member to pivotally secure it to a roadbuilder blade.

5. In a push pole structure, a first member adapted to be secured to a push arm of a roadbuilder or the like, a pivot pin carried by said member adjacent the rear end thereof, a second member pivoted on said pivot pin and extending forwardly alongside said first member, means adjacent the front end of said first member to retain said members in adjacent relative positions with respect to each other and to permit floating of said second member relative to said first member, and means at the front end of said second member to pivotally secure it to a roadbuilder blade.

6. In a push pole structure, a first member adapted to be secured to a tractor operating a roadbuilder or the like, a pivot pin carried by said first member, a second member having its rear end pivoted on said pivot pin, a third mem-

ber pivoted to the front end of said second member, means for securing said third member to a roadbuilder blade, said second member having a pair of spaced flanges and a slot aligned with the space between said flanges, a latch plate pivoted between said flanges and adapted to extend through said slot and selectively coat with one of said notches of said first member, and a bolt through said flanges and through said latch plate to retain it in either latching or non-latching position.

7. In a push pole structure, a first member comprising a plate adapted to be secured to the side of a push arm or the like, said member having a pair of flanges overlapping the top and bottom of said push arm, said flanges having perforations to receive an attaching pin for mounting said member on said push arm, said plate having a plurality of vertically spaced notches adjacent its forward end, said plate adjacent its rear end having a reinforcing member including a plate spaced from said first plate and rigidly secured relative thereto, a pivot pin carried by said plates, a second member comprising a plate having its rear end perforated and located between said pair of plates with said pivot pin extending through the perforation thereof, said second plate having a pivot perforation at its front end, a third member including a pair of plates between which said front end of said second member extends, a pivot pin carried by said last pair of plates and extending through said perforation of said front end of said second member, means for securing said third member to a roadbuilder blade, said second member having a pair of spaced flanges and a slot aligned with the space between said flanges, a latch plate pivoted between said flanges and adapted to extend through said slot and selectively coat with one of said notches of said first plate, means through said last flanges and through said latch plate to retain it in either latching or non-latching position, and a reinforcing plate secured to said second plate and having a spaced portion between which, and the second plate, the forward end of said first plate is slidably mounted, said reinforcing plate having a slot to receive said latch plate in its latched position.

8. In a push pole structure, a first member comprising a plate adapted to be secured to a push arm of a tractor operating a roadbuilder or the like, said member having a pair of flanges overlapping the top and bottom of said push arm, said flanges having perforations to receive an attaching pin for mounting said member on said push arm, said plate having a plurality of vertically spaced notches in its forward end, a pivot pin carried by said plate adjacent its rear end, a second member comprising a plate having its rear end perforated and receiving said pivot pin, said second plate having a pivot perforation at its front end, a third member, a pivot pin carried thereby and extending through said perforation of said front end of said second member, means

for securing said third member to a roadbuilder blade, a latch plate pivoted to said second member and adapted to selectively coat with one of said notches of said first plate, and means through said latch plate to retain it in either latching or non-latching position.

9. A push pole structure comprising a first member including a plate secured to the side of a push arm or the like, said plate having a recess adjacent its forward end, said plate adjacent its rear end having a pivot pin, a second member including a plate having its rear end pivoted on said pivot pin, a third member pivoted to the forward end of said second member, means for securing said third member to a roadbuilder blade, a latch carried by said second member and adapted to selectively coat with said recess, and means coacting with said latch to retain it in either latching or non-latching position.

10. In a push pole structure, a first member adapted to be secured to the side of a push arm of a roadbuilder or the like, said member having a plurality of vertically spaced notches in its forward end, said member adjacent its rear end having a pivot pin, a second member having its rear end perforated and receiving said pivot pin, said second member having a pivot perforation at its front end, a third member including a pivot pin extending through said perforation of said front end of said second member, means for securing said third member to a roadbuilder blade, said second member having a pair of spaced flanges, a latch plate pivoted between said flanges and adapted to selectively coat with one of said notches of said first member, and a bolt through said flanges and through said latch plate to retain it in a selected latching position.

11. In a push pole structure, a first member adapted to be secured to a tractor or the like and including a vertical plate having vertically spaced notches in its forward end, a second member pivoted to said first member, a third member coacting with said notches and with said second member to retain said first and second members in relatively fixed positions with respect to each other, said second member being freely movable relative to said first member when said third member is in a non-coacting position with respect to said notches, and means to secure said second member to a roadbuilder blade or the like.

12. In a push pole structure, a first member adapted to be secured to a tractor or the like and including a plate having notches therein, a second member adapted to be secured to a roadbuilder blade or the like, said second member being movable relative to said first member, a latch pivoted to said second member and adapted to enter one of said notches of said first member to retain the second member in a fixed position relative to the first member, said second member, when said latch is free of said notches, being movable relative to said first member.

ELSWORTH W. AUSTIN.
